COVER CLAMPING MEANS FOR BEDSTEADS

Filed Aug. 1, 1927

By *W. E. Chapman*

W. S. McDowell, Attorney

UNITED STATES PATENT OFFICE.

WILLIAM ELMER CHAPMAN, OF COLUMBUS, OHIO.

COVER-CLAMPING MEANS FOR BEDSTEADS.

Application filed August 1, 1927. Serial No. 209,776

This invention relates to an improved attachment for bedsteads and the like for the purpose of providing positively acting means for clamping the bed covering in an applied or operative position and to prevent the covering from losing such positions by the movements of the occupants of the bedstead.

It is the common practice to secure such covering by tucking the marginal edges thereof in between the mattress and the spring frame of a bedstead. If, however, the occupant changes his position while sleeping, the covering is readily removed from its mere frictional engagement with the mattress and spring frame and thus uncovers or readily admits of the uncovering of the sleeping person. This is particularly true in the case of infants or children.

It is therefore an outstanding object of the present invention to provide a simple readily applied attachment to the frame of a bedstead which will serve effectively for securely clamping the covering in position and to prevent the accidental withdrawal of the covering from its protecting position over the occupant of the bed as such occupant moves to change his sleeping position.

It is another object of the invention to produce a clamp of this character which will not injure, tear or mar the bedcovering or the bed frame with which it is associated.

A further object of the invention rests in constructing the attachment so that it can be readily applied to or removed from the frame of the bedstead.

With these and other objects in view, as will appear as the description proceeds, the invention consists in the novel features of construction, combinations of elements and arrangements of parts hereinafter to be more fully described and pointed out in the appended claims.

In the accompanying drawing:

Figure 1 is an end elevation of a bedstead provided with the covering fastening means comprising the present invention,

Figure 2 is a top plan view of one end of the attachment,

Figure 3 is an enlarged front elevation of a fragmentary portion of the attachment,

Figure 4 is an enlarged vertical sectional view taken on the plane indicated by the line 4-4 of Figure 3.

Referring more particularly to the drawings the numeral 1 designates the foot end

structure of a bedstead. In this instance the bedstead has been shown as comprising a U shaped frame 1 with which is connected a transversely extending angle member 2 and longitudinally extending side members 3, all of ordinary construction and adapted to provide a support for a mattress or the like 4.

The clamping mechanism consists of a pair of spaced plates 5, preferably of metallic construction. The lower end of each of these plates is formed to include a laterally extending foot 6, which rests upon the upper surface of the angle bar 2, the extreme lower part of each plate being arranged for engagement with the rear surface of the vertical leg 7 of said angle bar. This construction is shown particularly in Figure 4, and one method of retaining each plate in their operative position is to provide a pair of screw clamps 7 which, when tightened, firmly secure the plates in position but permit of their convenient removal from the bedstead when the covering attachments are not used.

The upper end of each plate is provided with a vertical finger 8, substantially square in cross-section. The finger of each plate is receivable within a substantially square opening provided in the ends of a longitudinally extending concave clamping bar 9. The under side of this bar is provided with a sack 85 or other similar covering 10 which protects the sheet, blanket or bed covering generally from wear and tear.

The plates 5 are united by a unitary longitudinally extending shaft 11 which may be either integrally formed with the plate or suitably secured thereto. The shaft 11 is of rounded formation and the clamping bar 9 is shaped to engage with the upper surface thereof. It will be understood that the shaft 11 and the bar 9 extends longitudinally from one plate to the other.

The bar 9 has its ends provided with upturned tongues 12, with which are engaged chains 13, the latter having their lower ends connected with coil springs 14 which latter have their lower ends connected, in turn, with a recess 15 provided in the outer side edge of each of the plates.

In operation, it will be seen that when the plates 5 and the associated shaft 11 are secured to the bed frame, the clamping bar 9 may be elevated against the resistance offered by the springs 14. This permits the marginal edges of the bed covering 10 to be inserted

between said clamping bar and the upper surface of the shaft 11, whereby when the clamping bar is released the springs 14 return the same toward the shaft so as to exert 5 the frictional pressure upon the covering to prevent the same from being accidentally removed from its applied position on the mattress. If it is desired to remove the attachment at any time this can be done by simply 10 loosening the clamps up, which permits the clamping attachment as a whole to be readily removed from the bed with the expenditure of but little time and labor.

While I have described what I consider to 15 be the preferred form of the present invention, never-the-less, it will be understood that various changes and modifications may be made therein from time to time from the specific form of the invention above set forth 20 without departing from the spirit and scope of the invention as the latter is defined in the following claims.

What is claimed is:

1. A bed cover clamp comprising a pair 25 of end plates and a longitudinally extending bar connecting said plates, upstanding guards formed with said plates, a clamping bar slidably mounted for movement relative to said first named bar and having the ends thereof 30 provided with openings for the reception of said guards, tongues formed with the ends of said clamping bar, and spring means at-

tached to the plates and detachably connected with the tongues of said clamping bar.

2. A cover clamping attachment for bedsteads comprising a frame consisting of spaced end members and a rigidly associated longitudinally extending connecting member, means for detachably securing the end members of said frame in an applied position upon 35 a bedstead, vertical guards provided in connection with the end members of said frame, a clamping bar slidably mounted for movement relative to said connecting member, and resilient means cooperative with said clamping bar for maintaining the same normally in engagement with said connecting member.

3. An attachment for securing the covering of beds comprising a pair of spaced end plates, securing means for attaching the lower 40 ends of said end plates to a bed frame, a longitudinally extending connecting bar rigidly uniting said end plates, upstanding guards provided in connection with said end plates, a curved clamping bar extending longitudinally of said connecting rod and having the ends thereof provided with openings for the reception of said guards, and spring means 45 connected with the end of said bar and with said plate and normally serving to maintain said bar in clamping engagement with said connecting rod.

In testimony whereof I affix my signature.
WILLIAM ELMER CHAPMAN.
